UNITED STATES PATENT OFFICE.

LEWIS T. HOUGHTON, OF WORCESTER, MASSACHUSETTS.

TENSION DEVICE.

Application filed December 26, 1922. Serial No. 608,882.

To all whom it may concern:

Be it known that I, LEWIS T. HOUGHTON, a citizen of the United States, residing at Worcester, in the county of Worcester and State of Massachusetts, have invented a new and useful Tension Device, of which the following is a specification.

This is a continuation, in part, of my prior application Serial No. 532,001, filed

10 January 26, 1922.

This invention relates to a tension device for use in spooling or winding thread, yarn or the like. The principal objects of the invention are to provide a self acting and practical device of this character of such a nature as actually to secure the long desired result of a substantially constant tension, and therefore uniform winding, under all variations in speed and other 20 changeable conditions; to provide a device which instantly and automatically responds to the most minute variations in pull on the yarn; to provide means for actually changing the number of points at which tension is applied to the yarn while it is running through the tension device in order to neutralize the changes in tension; to provide for automatic action in two ways both having the effect of bringing the yarn tension back to normal; and to provide a device of this character with means for balancing the normal minimum drag to the desired tension so as to render it suitable for fine or weak thread or yarn and yet leave it in such 30 condition as to operate automatically in the two ways just mentioned.

Further objects and advantages of the invention will appear hereinafter.

Reference is to be had to the accompanying drawings, in which—

Fig. 1 is a plan of a tension device constructed in accordance with this invention and said prior application and showing the yarn in a position which it frequently assumes;

Fig. 2 is a right end elevation of the same with the guides in section;

Fig. 3 is a front elevation but showing the tension fingers all down in their lowermost position;

Fig. 4 is a left end elevation of the tension device;

Fig. 5 is a sectional view on the line 5—5 of Fig. 4, showing details of the tension device;

Fig. 6 is a sectional view on the line 6—6 of Fig. 4;

Fig. 7 is a plan of a preferred form of the invention;

Fig. 8 is a sectional view on the line 8—8 of Fig. 7; and

Figs. 9 and 10 are opposite end views.

The art of spooling and winding.

In the spooling of yarn from filling wound bobbins there are several causes for variation in strain on the yarn that have to be compensated for by an elastic tension device in order to secure uniform winding on the spool. The yarn is wound from a bobbin or cop from a conical surface and it plays up and down the side of this conical surface during the winding operation. Obviously the diameter of the convolution of yarn from which it is being drawn varies 75 constantly as it comes successively from different layers in different vertical positions on the bobbin. It also varies with the position from which the yarn is taken on the bobbin as the bobbin is unwound more and 80 more. Another variation is due to the ballooning of the yarn and consequent air resistance. When the yarn is being wound from a point near the bobbin itself, the rapidity of revolution is greater than it is 85 when it is being wound from the circumference of the original yarn package. In fact, in the former case the rotations are about twice as fast and the air resistance necessarily varies to the same degree. It 90 will be seen that some of these variations occur rapidly, that is from 50 to 100 times a minute while others change slowly as the yarn approaches the end of the bobbin. In addition to that there are irregular variations due to irregularities and imperfections in the yarn or in its winding on the bobbin and consequent momentary and sudden increases in the resistance of the yarn.

There is also another variation which is 100 slow and cumulative due to the fact that, when winding on the spool, the spool speed is constant but, as the yarn winds on it and the diameter on which it is wound increases, the speed of the yarn through the tension 105 device will gradually increase by uniform gradations so that a tension device ordinarily is not equally effective throughout the entire body of the yarn wound on a single spool.

It will be seen, therefore, that the speed of the yarn gradually and uniformly increases during the winding operation but the other changes are alternating in character and most of them sudden, some being regular and some irregular. The great variation in size and material of yarn, from silk to asbestos covered wire and the variation in size and shape of these yarn packages obviously present varying conditions for spooling yarn.

The prior art.

It has been usual heretofore to design the tension devices, intended for overcoming some of these various difficulties, for the particular material on which they are to operate. I will not describe all the different prior devices but for the winding of filling wound yarn numerous devices have been invented which, so far as they relate to the present invention, may be described as coming in two groups. One of these is represented by my own prior patents in which a series of horizontal guides support the yarn and a series of tension fingers alternating with them rest on the yarn and swing about a transverse pivot. The variations in drag are intended to be compensated for by the drag itself acting to raise the pivoted fingers and reduce the amplitude of the undulations of the yarn through the tension device.

Another form of tension device has been proposed, but not successfully used as far as I am aware, in which there is a fixed series of yarn guides and a pivoted series, the pivot being arranged on an axis parallel with all the yarn guides. The pivoted series was intended to be operated at a distance from the movable series and to move toward them upon an increase in drag for the purpose of reducing the tension in that way to partially compensate for an increase in drag. These have always, as far as I know, been dependent upon either weights or springs, which would vary in effect, in accordance with the different positions of the pivoted guides, and which could not be adjusted to take care of all kinds of yarn and particularly wire. In some of these devices it has been claimed that the movable guides could go out of action when enough drag was put upon them, but they have all been so constructed that they were intended to be operated normally with all the guides in contact with the yarn and it would be only after a very great pull on the yarn, such as would not occur often in ordinary practice, that the movable ones would be moved substantially into the field of the stationary ones and some of them might move out of contact with the yarn. There has been no means of adjusting such devices so that both of these actions could always during opera-

tion take place instantaneously and on slight change in strain, so that the device would work normally in such a way as to provide for relieving both great and small changes in strain, by the yarn itself, instantaneously and accurately all through the extent of the several variations in strain above mentioned. In other words, they have not succeeded in accomplishing the result of securing an even tension throughout both the constantly repeated small variations and the irregularly occurring and relatively great variations in drag that are incident to the winding and spooling of yarn of all kinds.

I find that none of the above devices has a universal application even in the industry of winding yarn. They all have to be designed or adjusted for any considerable difference in the number or size of the yarn and especially for different kinds of yarn. Even when used for the particular size, kind and quality of yarn for which they are designed, they lag behind and are not capable of securing an even tension through the entire unwinding of the yarn from a single bobbin or cop. Consequently they do not always lay the yarn evenly on the spool or other article which is being wound and the yarn itself therefore will vary in elasticity as it is laid on the spool and furthermore the more accurately and finely they do work the more breaks in the yarn will occur. Thus, if these types of tension devices, in which there is a series of pivoted fingers or guides, work so as to secure ordinarily a reasonably even tension they will, when subjected to a sudden strain, move so far as to release all tension and then their consequent sudden recoil will deliver a sharp blow to the yarn and sometimes break it.

The purpose of this invention.

This invention is designed to make use of the advantages of the above mentioned devices causing changes in velocity whether small or great, gradual or sudden, continuous or intermittent, to tend to relieve themselves by their own action, first by straightening the yarn path and second by automatically and immediately reducing the number of yarn contacts with the yarn guides or tension fingers. I arrange the parts so that both of these methods of relief are always ready to act at once and there is no appreciable time when either of them cannot act instantaneously. At the same time I adjust the tension device in such a way that, from the slowest speed at which the yarn moves normally up to its maximum speed, the device will operate, always vibrating between its lowest and highest point, and that the changes in position will take effect when the velocity changes so as to compensate for it immediately and this compensation will be accomplished solely by the

yarn itself. In case of increasing yarn strain the drag will be relieved just enough to overcome it. At the same time these improvements enable me to run the winding operation for any size yarn at a much higher speed than has ever been done before, thus increasing production and reducing cost as well as improving the yarn package and also improving the yarn itself by conserving its elasticity and reducing breakage to a minimum.

This invention also accomplishes the winding in such an even manner and accommodates itself to the existing conditions so thoroughly that the same device can be used for a great many more sizes of yarn without adjustment than has been the case with any device made heretofore of which I have knowledge.

It involves, as the other devices, two sets of yarn guides, preferably one being stationary and the other being pivoted or otherwise movable. The movable yarn guides I call tension fingers because they create drag and therefore tension on the yarn or other material passing over the stationary guides by applying pressure to it. I have heretofore designed the movable guides so that their weight, acting on the yarn furnishes the necessary pressure and that principle I have retained here but I have added to it another feature, namely the use of an adjusting means by which the weight or pressure of the movable guides can be adjusted to the yarn conditions existing by adding to it or subtract from it (in the form shown on the second sheet), as the conditions may require. I also shape the fingers so that the yarn path varies its position on them so that scoring will not always take place at the same point. This increases the life of the guides.

First sheet of drawings.

Referring now to the first sheet of drawings, I will describe more specifically a practical device for securing the above mentioned results. Although capable of general use, I have shown the invention as applied to a spooling machine in which a strand of yarn Y is taken from a bobbin or cop B and wound on a spool S on the spooler. No other elements of the spooling machine are shown or described except the usual rail R, as this invention is not limited to any particular kind of winding or to the horizontal position.

Over the rail R I provide a sheet metal bracket 9. This bracket can be fixed to the rail by a bolt 10 or in any other desired way and is fixed in absolutely stationary position. One of these brackets is used for each tension device and for each spool a series, as for example four, of stationary yarn guides 12 shown in substantially hori-

zontal position though they can be located in any position. They are shown on a slightly upward incline toward the rail. I have shown them with upwardly inclined ends and a depression near each end, said depressions being in a row and constituting what amounts to a horizontal groove. The plate 11 which supports these guides is provided with a pair of parallel ears 13 perforated for a rotatable rod or shaft 14. This rod extends outward at the outer end and is bent at 15 to provide a handle for use in manipulating it. On this rod is securely fixed a plate 16 of sheet metal from which extend a series of tension fingers or yarn guides 17.

I have shown the shaft 14 parallel with the plane of the series of yarn guides 12 but perpendicular to their length so that the device can be threaded simply by turning them back and laying the yarn on the stationary guides. I have shown the fingers 17 as extending from the top of said plates at different heights but in alignment with each other and I have preserved this situation with respect to their active portions. Therefore, the parallel and substantially horizontal active portions of these fingers 17 are in a plane inclined with respect to the plane of the fingers 12. Beginning at one end of the series, each finger 17 is at a greater distance from the plane of the fingers 12 than the one on that side of it when these fingers are in their lowest position. As the movable fingers swing, the angle which each makes with the plane of the fixed fingers varies. Therefore the position of the yarn on them changes a little. This distributes the wear and prevents grooves forming in the fingers due to the travel of the yarn across them. I have also shown the ends of the fingers as bent over at 18 downwardly.

In the lowest position in which they can rest the highest one is nearly in the plane of the stationary fingers so that it is ready to be lifted above them on any increase in yarn drag above its minimum.

The parallel ears 13 above mentioned can be made integral with the vertical plate 11, if desired, but I prefer to provide an adjustment and for this purpose they are mounted on a plate 20 which fits against the back of the plate 11 and which is secured to that plate by a bolt 21 and nut 22, the bolt passing through a vertical slot 23 in the plate 11. This plate 20 is provided with two integral projections 24 extending forwardly through the slot 23 and fitting its opposite sides so as to constitute a guide for keeping the plate 20 always in the same angular position independently of its vertical adjustment. The plate 16 is provided with downwardly projecting ears by which it is fixed to the shaft 14 and it is also pro-

vided with a projection 19 which, when the plate is moved over to its limiting position, engages the back of the plate 11 and prevents further motion in that direction.

5 This constitutes the limiting means.

I have provided on the shaft 14 a rotary toothed wheel 30. It is freely mounted on the shaft and is capable of turning and sliding both. On the plate 20 there is a

10 projection 31 which engages in one of the teeth of this wheel to hold it against turning, but the wheel is free to slide out of engagement with the projection 31 and to be turned. The purpose of this is to ad-

15 just the tension of a spring 32, one end of which is fixedly secured at one end to this wheel. This spring is wound around the shaft 14 and the other end 33 presses against the plate 16 so that the tension of

20 the spring serves to assist gravity in holding the tension fingers down in active position and this tension can be adjusted as desired.

I have also provided means for locking 25 the gear wheel against sliding motion, this being shown in the form of a notched lever 35 which is secured to the plate 16 by a screw 36 so that when it swings so that the shoulder 37 moves against the wheel as 30 shown in full lines in Fig. 4 the wheel is prevented from being displaced along the shaft. When it is desired to adjust the spring the screw 36 is loosened and the outer end of this lever moved up so the wheel is 35 free to slide along the shaft out of engagement with the projection 31.

In this device the yarn moves through 40 a clear path which is always open to view and on the surfaces of which no waste can collect to impair the tension as in many other devices. The device results in uniform tension.

Operation.

45 In operation, the operator moves the handle 15 over to swing the movable tension fingers back to the dotted line position shown in Fig. 6 and the yarn is laid on the lower yarn guides. Then the movable fingers are allowed to swing back toward the 50 stationary ones and they draw the yarn down between them to cause the yarn to pass up and down along the sinuous path. The guides are so arranged that, at a minimum 55 velocity, one of the movable ones is close to the yarn path just ready to be lifted above it at the slightest increase in yarn drag. When the yarn passes through the device every resistance that it encounters 60 and every tendency to speed up adds to the force which it exerts on the movable tension fingers that are pressed down by gravity and by the spring. This force will lift the whole pivoted series and in operation the 65 yarn runs with this series of fingers sup-

ported by it and vibrating somewhat up and down. Just as soon as the yarn strain increases it lifts the movable fingers so far that the one at the highest level will come up above the yarn and cease to have any 70 effect upon it, the yarn passing over the two adjacent guides below without being depressed at all between them. In this way tension is taken off the yarn instantaneously because the number of yarn contacts and 75 undulations in the path of the yarn is diminished. Now, if the speed of winding slows up or the obstacle which caused additional strain is removed, there will be less force to hold the fingers up and they will 80 move back to normal position. This soon brings the fourth finger into contact with the yarn and adds therefore another tension area to it. This is an additional feature 85 over my tension devices because they have depended heretofore on the operation of a spring or an increase in the force of gravity or some such feature which was ordinarily not great enough to overcome the 90 variations which occur in the ordinary winding of yarn or threads. Now, without giving up those advantages, I have provided a means for varying the number of areas at which tension is applied to the moving strand of yarn and the action does not 95 lag behind its course because there are no weights or springs that vary the tension by changes in leverage, friction or compression. As the yarn path starts to straighten there is no increased resistance due to intervening weights or springs. 100

In this way, I have found in practice that I can wind yarn from a minimum practical speed to speeds higher than have been considered the maximum heretofore and with 105 the most delicate means which I have had for measuring the tension I cannot perceive that there is any difference in the tension. Furthermore, the yarn is wound uniformly and the number of breaks is very materially 110 reduced.

Second sheet.

The device above described and illustrated in Sheet 1 of the drawings is the one disclosed in my above identified application. It has proved an important and valuable addition to this art but I find in actual mill practice that it has certain limitations. The guides and fingers must be made of large 115 enough wire so that the constant scoring of the yarn, which necessarily takes place in this art, will not soon render them unfit for use. For that reason the minimum weight of the whole set of movable fingers is necessarily limited. Fingers made of a practical 120 size and a practical length are suitable for use with certain kinds of yarn but they are somewhat too heavy for use with the finer or weaker grades of yarn. Furthermore 125 130

the movement of a set of relatively heavy fingers lags behind the sudden and momentary changes in drag so that it does not correct them rapidly enough for some kinds of work. Moreover in Sheet 1 as originally described nothing was said about any means for decreasing the pressure to permit its use for relatively fine or weak yarn or to enable it to be used in any but a horizontal position.

10 I have discovered that by a very simple change in the construction above described with reference to Sheet 1, I can balance the drag to the desired tension and, at the same time, can use large wires for the movable tension fingers so that they will stand a lot of use and if they are normally too heavy for the yarn on which they are to be used, I can easily reduce their pressure on the yarn as well as increase it when conditions require it. In this way I can balance these fingers, whatever their original weight to any desired pressure on the yarn that may be necessary and at the same time the action of the fingers will be instantaneous. In

15 spite of the relatively large size of the fingers they will respond to changes in strain, either increase or decrease and do it instantly, without lagging behind them. Consequently the easement which they provide will take effect as soon as the change in strain has come into effect. I use this balancing feature for all sizes of yarns and it can be applied to constructions in which the guides and fingers are not horizontal.

20 25 I connect the spring 32^a, shown on the first sheet of drawings positively with the wheel 30 and I also bend its end 33^a around the edge of the frame 16^a so that it will tend to move it in either direction to balance it according to its adjustment. Therefore, this spring can be adjusted by means of the wheel 30 so that it will add to the force of gravity or other pressure due to the movable fingers or it will reduce the

25 30 same according to the conditions existing. This enables me to balance the drag against the desired tension. At the same time this adjustment can be made so delicate that, with whatever yarn or other material is to be used, the effect on the tension will be simultaneous with the change in strain which is to be overcome by it.

35 Before operation, the device must be adjusted so that with a minimum yarn velocity, (i. e. an empty spool) the drag will produce the desired tension. The drag just balances the tension thereby forcing the yarn itself to offset increase in strain by release of a corresponding amount of drag.

40 45 The drag is absolutely governed by the yarn itself and the yarn is compelled to control the drag.

50 55 This constitutes a fine adjustment which is particularly valuable in operating upon the finest and weakest grades of yarn and

enables me to use the same tension device for all grades without substituting heavier or lighter tension fingers when shifting from one kind of yarn to another. This enables me to use larger guides than were formerly practicable and thus increasing their life which is limited by their being scored by the yarn. In fact, I have found in practice that a device designed for spooling the finest grade of yarns can be employed without change, except the adjustment of the device, for winding copper wire covered with asbestos, which presents very different problems. I can balance the device to be so sensitive that it accurately and instantly compensates for all variations in spool speed and the spring can be used to provide just the necessary pressure even if the series of guides and fingers are not arranged in a horizontal position.

60 65 In addition to these features, I have provided a limiting spring, independent of the adjusting spring, for receiving any blow that might be imparted to the movable fingers by a sudden increase in strain, preventing their recoil back with sufficient force to break the yarn upon returning into contact with it. This does not act constantly but is a reserve cushion means adapted to come into action in case of a sudden change occurring. On the other hand, it is not positive as it yields with the blow of the fingers and returns them to their normal position gently. It also prevents the automatic opening of the fingers fully under any conditions in practice, but permits the operator to open them wide for threading purposes and also prevents their being accidentally left open so that they will not exercise their function of regulating the tension.

70 75 80 85 90 95 100 105 110 115 120 125 130

For the purpose of illustrating these facts I have shown on the second sheet of drawings a device constructed on the principle above described and balanced for the spooling of very fine yarns. In this case the features that have been described heretofore are all shown and are given the same reference characters as above so that the description referring to the first sheet of drawings will also apply to the second sheet. The coiled spring 32^a is here fastened to the toothed wheel 30 at one end and the other end hooked over or fastened to the pivoted guide holding plate 16^a. This construction provides for exactly balancing the drag against the desired tension or pull required to pack the yarn on the spool when the yarn is drawn through the guides at its slowest or normal velocity. When so balanced, if the yarn strain remained constant, these yarn guides would remain in their adjusted position. Any increase in yarn strain must raise the pivoted yarn guides and release a corresponding amount of yarn drag; thereby maintaining a constant tension.

The yarn itself regulates or controls its drag. For illustrating an extreme case, I have shown the device in a position balanced by adjusting the wheel 30 in the way already described, so that a smaller number of the upper fingers 17^a are in contact with the yarn when the yarn is running at a minimum operating velocity, if it should be desired. The movable fingers in practical mill use all intermesh and are arranged or adjusted so that in the lowest position to which they can go the highest one is just ready to move up out of yarn contact on a slight increase in strain. In other words, they are balanced so that upon increase in strain they will immediately begin to move toward a position in which the yarn contacts will be reduced.

In this case also I have shown an additional spring 40 fixed at one end to the shaft 14 and extending up over it and around under the frame 11^a where it has a hook to engage the frame or is fastened to the frame in any way. This is used because when the drag and tension are evenly balanced the sudden increase in yarn strain which often occurs causes the pivoted guides to suddenly "jump" out of yarn contact and their consequent recoil or rebound back on to the yarn often breaks it. This spring 40 prevents any excess movement of the guides. It is made yielding so that the operator can open the fingers for threading.

Another modification indicated here is that the series of fingers 17^a is shown as arranged in a straight line while the fingers 12^a are shown with those intermediate between the ends depressed below the plane thereof instead of in a straight line as in Fig. 2. When the yarn is passing over the first and last one without being depressed in the center, it will not engage the intermediate ones at all. It will be observed that if two fingers 17^a engage the yarn and cause two depressions or undulations in the yarn the yarn to the left of them will rest on the first and third fingers 12^a and will not touch the second. The making of the guides 17^a straight forces the yarn to change its bearing point as the guide is raised or lowered.

Although I have provided for reducing the cutting and scoring of the guides by the yarn, it cannot be entirely eliminated. In the form shown on Sheet 1, it is necessary to replace the entire device when even one of the guides becomes cut badly enough. In the form shown in Sheet 2 I make the guides 12^a and 17^a individually removable by screw threading them and attaching them in that way and I also harden them to make them last longer. I also place a thin hardened piece 49 detachably on the support 9^a for the same reason.

The device can be used on the coarsest yarns that are likely to be wound and the

same device without change in the number of fingers or their mounting can be balanced for use on the very finest and weakest of yarns and even for fine copper wire wound with asbestos.

Although I have illustrated and described only two forms of the invention, I am aware of the fact that other modifications can be made therein by any person skilled in the art without departing from the scope of the invention as expressed in the claims. Therefore, I do not wish to be limited to all the details of construction herein shown and described but what I do claim is:—

1. In a tension device, the combination with two sets of intermeshing guides arranged to engage a strand of material to be wound and cause it to traverse a tortuous path, one set being pivotally mounted in position to exert a substantially constant total pressure on the strand, irrespective of its yarn bearing position, and adjustable means for reducing or increasing the pressure thus exerted on the strand to balance the drag caused thereby against the desired tension, the last named means being connected to the pivotally mounted guides to maintain the same leverage thereon in all operative positions of the guides.

2. In a tension device, the combination with tension fingers resting their weight on the yarn with a constant pressure for providing the necessary drag, of means for balancing the drag produced thereby against the yarn strain, and means for maintaining the balance so that the tension will remain substantially constant with varying yarn velocity or strain.

3. In a tension device, the combination with a set of movable tension fingers, of a shaft connected with them about which they swing through an arc to bear against the yarn, a spring for holding them yieldingly in operative position, said spring being arranged to apply a substantially constant resistance to the motion of the tension fingers in all their operative positions, and means for adjusting the pressure of the spring.

4. In a tension device, the combination with a set of movable tension fingers, of a shaft connected with them for moving them through an arc, a spring coiled on the shaft for holding them yieldingly in operative position, and a toothed wheel free on the shaft to which wheel one end of the spring is fixed, said wheel being capable of being turned on the shaft to adjust the tension of the spring.

5. In a tension device, the combination with a set of movable tension fingers, of a shaft connected with them for moving them through an arc, a spring for holding them yieldingly in operative position, a toothed wheel free on the shaft to which wheel one end of the spring is fixed, said wheel being

capable of being turned on the shaft to adjust the tension of the spring, and means for locking the wheel.

6. The combination of a fixed series of 5 yarn guides, a pivoted series of yarn guides arranged to pass through and between the fixed series, and to rest by the force of gravity in a position with all of them below the fixed series, so that the yarn passing 10 over one fixed guide and under one pivoted guide, when so threaded through the two series, supports the pivoted series and forms a tortuous yarn path, a spring to provide the pressure desired on the yarn, and a 15 means for adjusting the force of the spring.

7. In a tension device, the combination with a set of yarn guides and a relatively movable set of alternately located tension fingers mounted to exert as a whole a constant pressure on the yarn or thread and arranged to move out of, or into, contact with the yarn one by one as the velocity and strain vary, and means for yieldingly holding the fingers in such position that at all 20 times a small change in velocity or strain will instantaneously change the number of 25 yarn contacts.

8. In a tension device, the combination with two series of intermeshing yarn guides, 30 the several guides of one series being movable to the same extent toward and from the other and being located at unequal distances from the adjacent ones of the other series, of a shaft on which the movable guides are fixed, and a spring adjustable to 35 vary the effective pressure of the pivoted guides on the yarn.

9. A yarn tension device having, in combination, a series of fixed yarn guides across 40 which the yarn passes in its course in the machine, and a series of movable yarn fingers under which the yarn passes, said movable fingers alternating with the fixed yarn guides and pressing upon the yarn with a 45 constant pressure, yielding means acting upon said fingers with a resistance that is substantially constant at all times while the 50 yarn is running, and means for adjusting said yielding means so as to augment or diminish the pressure of the movable fingers upon the yarn, whereby the effective pressure 55 may be balanced with respect to the varying normal tensions desired for different 60 yarns.

10. A yarn tension device for a spooling machine having, in combination, a series of 65 fixed yarn guides over which the yarn passes in its course in the machine, and a series of movable yarn fingers beneath which the 70 yarn passes, said movable fingers alternating with the fixed yarn guides and being all carried by the same pivoted support and pressing upon the yarn which upholds them, a spring 75 acting upon said support, and means for adjusting said spring so that it may add to

the downward pressure of the movable fingers upon the yarn or may variably counterbalance the weight of the fingers, whereby the effective pressure may be balanced with respect to the varying normal tensions 80 desired for different yarns.

11. A yarn tension device for a spooling machine having, in combination, a series of fixed yarn guides over which the yarn passes in its course in the machine, and a series of 85 movable yarn fingers beneath which the yarn passes, said movable fingers alternating with the fixed yarn guides, a support pivoted on an axis substantially parallel with the path of the yarn, on which support all of said fingers are carried in position to press upon the yarn which upholds them, the several movable fingers being located in all positions at varying vertical distances from their corresponding fixed guides, a spring acting upon 90 said support, and means for adjusting said spring so that it may add to the pressure of the movable fingers upon the yarn or may variably counterbalance the pressure of the fingers, whereby the effective pressure may be balanced with respect to the varying normal 95 tensions desired for different yarns.

12. In a tension device, the combination of two series of guides arranged alternately to engage the material being wound and cause it to traverse a sinuous path, one set being movable, and means for yieldingly limiting the movement of the movable guides away from the other series, said means becoming effective at any desired 100 point of their intermeshing.

13. In a yarn tension device for winding and spooling machines, the combination of two series of guides arranged to form a tortuous path for the yarn and exert pressure 105 upon it to create yarn drag, means for adjusting the pressure exerted by the guides to provide suitable drag at any desired velocity of travel of the yarn and when its velocity is less than its maximum, and means 110 whereby whenever at any time the yarn velocity or strain increases the increase will automatically and immediately move one set of guides enough to remove one of the guides from contact with the yarn and thereby reduce the drag on the yarn and keep the tension constant by the action of the yarn 115 itself.

14. In a yarn tension device, the combination with two sets of relatively movable guides for engaging the yarn, one of them being arranged to exert a constant pressure on the yarn in all its yarn contacting positions, of adjustable means for exerting pressure to provide the necessary drag on the 120 yarn so that the drag will be balanced against the desired tension when the yarn velocity is below its maximum, whereby any increase in velocity will reduce the drag 125 enough to maintain the tension for which 130

the device is balanced, said adjustable means being constructed and arranged to exert a substantially constant resistance against the separation of the guides, in any adjusted position.

15. In a tension device for a strand of flexible material, the combination with a series of tension fingers mounted and arranged to apply a substantially constant total pressure to the running strand and arranged to be moved by the strand as its strain and velocity vary to change the length of the undulations and the number of yarn contacts by the action of the yarn itself, and means adjustable to increase or decrease the amount of said total pressure at will for the purpose of securing the desired tension, the last named means also being arranged to act with a substantially constant resistance against the outward motion of the tension fingers in any operative position thereof, whereby the tension will remain constant.

16. In a tension device for a running strand or thread, the combination with means acting at a plurality of points on the strand for producing a substantially constant total pressure on the strand at all times irrespective of changes in the velocity of the strand and the strain on it, of means for adjusting the pressure of said means to vary its total pressure on the strand and balance said pressure against the desired tension, said adjusting means being capable of being adjusted to either increase or decrease the total pressure at will, said pressure means being arranged to move with variations in the velocity and yarn strain and instantaneously, at all times while the strand is running, vary the length of the undulations of the yarn and number of yarn contacts.

17. In a tension device, the combination with guiding means for the yarn or thread, of a series of movable tension fingers engaging the yarn or thread alternately with said guiding means, exerting pressure due to gravity thereon, and capable of moving toward and from the guiding means with variations in velocity and strain and located at different distances from the guiding means and at all times, while the yarn is under tension, close to them so that the

number of yarn contacts will vary instantaneously as they move, means for supporting said fingers with a minimum drag upon them in such position that an increase in strain at any time will automatically reduce the number of yarn contacts, and yielding means for adjusting the position in which the fingers are supported to balance their pressure on the yarn to the desired tension, substantially as described.

18. In a tension device, the combination of a series of stationary substantially horizontal yarn guides for supporting a strand of yarn passing over them having collectively a trough with oppositely slanting sides for receiving the yarn, with a corresponding series of straight tension fingers above them adapted to pass down between said yarn guides, said fingers being supported by the yarn and pivoted on a transverse axis and located at all times and in all possible positions at varying vertical distances from the adjacent guides, and in such relation to the sides of said trough that the position of wear will vary as they swing away from normal position, said tension guides and fingers being relatively movable and so located relative to each other that the number of fingers which actually pass below the guides and contact with the yarn will be automatically reduced when the drag is increased beyond a certain amount of compensate for it and will be increased again when the pull on the yarn is similarly decreased.

19. In a yarn tension device, the combination of two series of intermeshing yarn guides arranged at varying distances from each other forming a tortuous yarn path, one series being pivoted on an axis parallel with the general direction in which the yarn moves, yielding means for providing a constant yarn tension, means for balancing the yarn drag against the desired tension, and yielding means for providing resistance against the lifting of the pivoted series at any desired point, thereby preventing abnormal lifting and consequent recoil.

In testimony whereof I have hereunto affixed my signature.

LEWIS T. HOUGHTON.
